[57] CLAIM

The ornamental design for a tooth-shaped sand timer, as shown and described.

DESCRIPTION

FIG. 1 is a perspective view of a tooth-shaped sand timer showing my new design.

FIG. 2 is a front elevational view thereof on a reduced scale, the rear view being substantially similar thereto but with the 'face' omitted and the base being flat;

FIG. 3 is a right-side elevational view thereof on a reduced scale, the left side being a mirror image thereto.
